 New York, N. Y., a corporation of New York

Application May 14, 1938, Serial No. 208,086

9 Claims. (Cl. 95—4.5)

This invention relates to a novel record controlled machine and more particularly to a photographic recording machine controlled by a film control record having controlling representations, such as light modifying areas, to condition light responsive means which in turn are adapted to control photographic recording devices in accordance with the controlling representations disposed on the control record.

One of the objects of the present invention resides in the provision of photographic recording means controlled by and in accordance with the various light modifying characterizations disposed on the film control record to list photographically the indicia corresponding to the said characterizations.

Another object of the present invention resides in the provision of photographic recording means controlled by and in accordance with the light modifying characterizations disposed on the film control record to form a suitable machine control record having control representations disposed thereon similar to those disposed on the first mentioned control record.

Another object of the present invention resides in the provision of photographic recording means controlled by and in accordance with the light modifying characterizations disposed on the film control record to form a photographic record of the indicia corresponding to the said characterizations and simultaneously therewith form a machine film control record having control representations disposed thereon similar to those of the first mentioned control record.

Another object resides in the provision of means to control electronic devices in accordance with the data sensed on a control record to control photographically the listing of the data and/or reproducing the data representations sensed.

Another object is the provision of means whereby differentially timed impulses are initiated upon sensing control records to control photographically the listing of the data and/or reproducing the data representations sensed.

Another object is the provision of means whereby the photographic listing of data and/or reproducing of data representations is effected automatically upon sensing successively groups of control data representations.

Another object is the provision of means whereby the photographic recording means is controlled differentially to indicate the control data sensed and photographically list the data and/or re-

produce the data representations of the data representations sensed and indicated.

Other objects of the invention will be pointed out in the following description and claims and illustrated in the accompanying drawings, which disclose, by way of example, the principle of the invention and the best mode, which has been contemplated, of applying that principle.

In the drawings:

Fig. 1 is a detail view of a fragmentary section 10 of the film machine control element.

Fig. 2 is a detail view of a fragmentary section of the listed data upon an opaque photographic record medium.

Fig. 3 is a perspective view of the assembled 15 machine.

Fig. 4 is a sectional view along the lines 4—4 of Fig. 3 showing the control elements of the machine control record advancing and sensing means.

Fig. 5 is a plan view of the device shown in Fig. 4.

Fig. 6 is a detail section of Fig. 5.

Fig. 7 is a sectional view along the lines 7—7 of Fig. 3 showing the control elements of the 25 photographic recording section.

Fig. 8 is a plan view of the recording section shown in Fig. 7.

Fig. 9 is a sectional view of Fig. 7 showing the mark of the recording section.

Fig. 10 is a detail view showing the relative disposition of control shafts of the recording section.

Fig. 11 is a detail view of the Geneva device used in the recording section.

Fig. 12a and Fig. 12b together show a circuit diagram of the machine.

General description

Briefly and broadly the instant embodiment of the invention discloses, by way of illustration, means whereby control data representations on a film control record are analyzed by modifying rays of light to condition light responsive means which are effective to control the conductivity of electronic control devices. Means are provided to be controlled by the latter to initiate differentially timed impulses at such times when the light rays are intercepted, or in other words when the data representations are sensed. The said 50 impulses are impressed upon control circuits including electromagnetic control means which upon energization at differential times are effective to cause data indicating means to be positioned in accordance with the data sensed to rep- 55

resent the data, whereupon automatically photographing means are rendered operative to record the data represented by the indicating means.

- 5 Shutter operating mechanisms are provided and operated at a timed interval after the sensing cycle to expose photographic record mediums through an objective included in the photographing means to the images of the data set up on 10 the indicating means so as to record the data. Two sections are provided in the photographic recording device, one in which indicator bars bearing the data to be sensed are differentially presented to viewing apertures and photographically recorded; that is, the data represented by 15 the coded representations on the machine control record are listed on opaque photographic paper or sensitized medium; in the second section indicator bars bearing code indicator spots are differentially positioned within elongated openings and photographically recorded, that is, the data 20 represented by the coded representations on the machine control record are reproduced in code on a film control record which may then be used 25 for a machine record control element.

Before describing the novel photographic recording device which forms the subject of the instant application, the photographic film control record will be first described.

30

Photographic control record

Referring now to Fig. 1 wherein a fragmentary section of the film control record 20 is shown, in 35 this figure, the perforations designated 21 represent the feed apertures in the film. The spot representations or light modifying areas 22 are photographic machine control characterizations representing control indicia such as numerical 40 data, and each set or group of numerical data comprises one or more control spot representations in such relative position upon the film record as to represent by their relative position 45 thereon the numerical control value thereof when the film record is trans-illuminated in the machine. In practice, such numerical spot representations are shown on the film in index point relation in general conformance with the manner in which index perforations are disposed or 50 perforated record cards in the Hollerith accounting system. That is, the differential position of a control spot representation delineates the numerical value of a particular numeral. This will 55 be clear by referring to the said figure, wherein it is noted that the data representations 22 represent the data photographically indicated at 23.

For a more detailed description of the film control record and certain applications of the described record such, for example, as a statistical system, reference should be made to the United 60 States Patent No. 2,124,906.

While in the present embodiment only numerical spot representations have been shown, such representations might indicate a letter or the letters of the alphabet or other symbols, and the 65 phraseology with respect to the control representations, such as light modifying areas, in the appended claims is intended to cover any such index point position representations.

It will be understood that the completed film 70 has photographic reproductions thereon at successively spaced intervals along the film as shown and that the reproductions are in extremely compact form. Accordingly, a large quantity of statistical information, or the like can be placed on 75 an extremely small controlling record. The films

used may be negative films or films which during development are transformed to positive. The film delineated is a positive.

Film control record advancing and sensing means

Referring now to Figs. 4, 5, and 6, wherein the film control record 20 is shown disposed on a supply spool or reel 25. The film is attached to a take-up spool 26, and may be advanced by suitable driving connections cooperating with shafts 27 and 28 by means of suitable film feeding sprockets 29 and 30 secured to the said shafts, respectively, adapted to cooperate with the film feed apertures 21 in the film record. The film is fed past an analyzing station comprising a scanning opening or aperture 31 and trans-illuminated by the light rays emanating from the light source 32 and directed thereto by the condenser 33. The said scanning aperture is adapted to present an opening sufficient to permit the scanning of a single transverse row of data or control representations only and is provided to extend transversely across the film record to any desired extent so as to permit the desired sections on the film to be scanned. The reference character 34 designates light responsive means, such as photo-cells, which are disposed at the analyzing station and adapted to be controlled by the light rays impinging thereon. Individual light conducting members 35 such as quartz rods suitably supported by member 36, extend from each photo-cell to the analyzing station where they are positioned adjacent to one another along the scanning aperture. The spacing of the said rods along the scanning aperture is so arranged that each rod is positioned opposite one of the columns of control representations disposed on the film record. In this manner the light rays directed to the scanning aperture can be conducted to the associated photo-cells to condition the latter for machine control operations during the film scanning or sensing operations.

The film advancing means and control means therefor comprise generally the clutch magnet 37 and associated pivoted armature 38 to which is secured a latch lever 39 normally engaging an extension 40 of the member 41 secured to shaft 28, and the clutch pawl 42 pivotally supported by member 41 and normally adapted to be disengaged from the clutch element 43 by means of the said latch lever. Upon energization of the said magnet the latch lever 39 is caused to release the pawl 42 to engage the clutch element 43 rotatably mounted on shaft 28 and rigidly secured to gear 44. The latter being in constant mesh with gear 45 which is driven by suitable means such, for example, as the drive pulley 46, secured to gear 45, motor 47 (Fig. 3) and the interconnecting driving connection 48. Thus it is seen that whenever the said motor and driving connections are operated and the magnet 37 energized that shaft 28 is rotated and also gear 49 secured thereto to rotate gears 50 and 51, the latter being secured to shaft 27, thereby rotating the said shaft, and causing the respective feed sprockets 30 and 29 to advance the film record past the analyzing or sensing station. The control representations 22 disposed on the film record are then effective to modify or intercept the light rays emanating from the light source 32 thus blocking off the light rays to the individual 60 and corresponding quartz rods 37 and associated photo-cells 34.

It should be mentioned that film supply control contacts C-1 (Fig. 6) are provided and adapted to be closed by the suitably pivoted lever 75

52 as long as the film control record 20 is presented to the analyzing station, however, when the film supply is exhausted the said lever is adapted to swing to the left as viewed in Fig. 6 to permit the contacts C-1 to open, the purpose of which will be understood as the description progresses. Also, suitably disposed contacts C-4 are provided to be controlled by cam 52-a, which is provided with a plurality of camming surfaces so as to operate the contacts at such times whenever the areas at which the differentially positioned control spots may appear are presented to the analyzing station, the purpose of which will be explained later.

15 *Photographic recording means*

Referring now to Figs. 7, 8, and 9, the photographic recording means is shown to comprise, generally, two sections, the first, a photographic data recording or listing device section capable of listing photographically the data represented by the control spot representations disposed on the film control record 20, refer to Fig. 2 wherein a fragmentary section of the said record sheet 20 is shown having a plurality of listed items disposed thereon; the second, a photographic machine control element recording section capable of recording photographically coded spot representations, in the form of light modifying areas, 30 to represent the data represented by the representations disposed on the film control record 20. In other words, the latter section is equivalent to a film reproducer to form a duplicate film record of the original film control record 20. The said sections are provided with a plurality of positionable indicator bars 55 and 56 to effect the data recording. The said bars 55 (Fig. 9) are provided with the individual characters, such as the numerical data indicated at 57, represented by the coded representations on the film control record 20, whereas each of the bars 56 are provided with single code spot indicators represented at 58. The said indicator bars are adapted to be positioned in synchronism with the advancement of the film control record 20 so that when recording upon the photographic records is about to be effected the said bars are positioned properly in accordance with the data representations sensed upon the said film control record. The positioned bars 55 representing the numerical characters represented by the sensed coded representations, and the positioned bars 56 representing the coded representations sensed on the control record 20.

55 Referring now to Fig. 7, the differential positioning of the indicator bars is shown to be effected by the cam 59 secured to shaft 60. Rotation of the said cam causes the pivotally mounted cam lever 61 to be raised and lowered according to the cam groove formed in the cam 59. Positioning of the cam lever 61 is effective by means of the connecting link 65 to raise and lower the bail arm 62, pivotally supported to the said arm. The bail 64 is adapted to cooperate with individual indicator bar control levers only one being shown and indicated at 66 and pivotally supported by the shaft 67 to permit the said control lever to be positioned upwardly by means of the associated spring 68 whenever the bail 64 is raised and to position downwardly the lever against the action of the spring when the bail is lowered. The described positioning of the control lever 66 causes the associated indicator bar to be raised and lowered accordingly by means 75 of the interconnecting link 69.

The upward movement of the indicator bar 55 is adapted to be interrupted by the rotatable stop pawl 70 whenever the pawl is released by the pivoted latch lever 71. The said latch lever is connected to the armature 72 of magnet 73 by the link 74 and upon energization of the magnet is positioned to the right as viewed in Fig. 7 releasing the spring urged pawl 70 so as to be positioned in the path of the indicator bar 55 and thus interrupt further upward movement thereof. It is to be understood that all the individual indicator bars 55 and 56 suitably disposed in the guide comb 56-a, are positioned in a similar manner.

It was mentioned hereinabove that the said indicator bars 55 and 56 are positioned in synchronism with the advancement of the film control record 20, by this it is meant that the film control record advancing means described hereinabove and the indicator bars positioning means 20 are operated in such timed relationship that when, for example, the control spot representations 22 disposed on the control record 20 (Figs. 1 and 4) in the "9" position are presented to the analyzing station, the group of indicator bars 55 25 are positioned so that the numeral characters "9" indicated at 57 are positioned to present the said numeral characters to the apertures or windows 75 (Fig. 9) and the group of indicator bars 56 are positioned so that the spot indicators 58 30 disposed on the last mentioned bars are presented to the elongated openings 76 in a position corresponding to the "9" position as indicated in Fig. 9.

The means provided to effect the said synchronous operations are as follows: referring to Fig. 4, gear 77 is shown secured to shaft 78 and in constant engagement with gear 45 which it is remembered is connected directly to the main driving means. In Fig. 7 clutch element 79 is 40 shown secured to the said shaft 78 and obviously is rotated whenever the driving motor is operated. Rotatably mounted on this shaft is gear 80 which in turn meshes with gear 81 secured to shaft 60. Upon energization of the magnet 45 82, the armature 83 is effective to release the clutch pawl 84, pivotally supported by gear 80, so as to engage the rotating clutch element 79 thereby rotating gears 80 and 81, shaft 60, cam 59 and the gearing generally indicated at 85 for 50 purposes to be set forth later herein. The ratio of the described gearing is such that whenever, during the sensing cycle, a group or set of control representations 22 disposed on the film control record 20 are presented to the analyzing 55 station the indicator bars 55 and 56 are adapted by means of the cam 59 and associated levers, during the said cycle, to present the numerical characters 57 progressively to the windows 75 and the spot indicators 58 to the openings 76 60 progressively in the different positions as indicated in Fig. 9.

The windows 75 and elongated openings 76 are provided in an opaque mask 86 which is positioned between the bank of indicator bars 55 65 and 56 and the record photographing means which will now be described.

The said photographing means consists of two sections, one capable of listing the items upon a photographic record or work sheet comprising 70 the diagrammatically shown lens system 87, chamber 88 having a recording aperture 89 and the photographic record sheet 90 and its associated advancing means. The other being capable of recording differentially positioned con- 75

trol spot representations upon a photographic film record capable of serving as a machine control element and comprising the lens system generally designated 81, chamber 92 having a recording aperture 89 and the photographic film record 94 and associated advancing means.

The lens system 81 is focused upon the mask 86 in a manner so that only the data appearing in windows 75 is directed or projected to the recording aperture 89 provided in the chamber 88, and the lens system 91 is so arranged that the coded representations appearing in the elongated openings 76 and the data appearing in the windows 75 and in addition thereto the supplemental data 96 provided directly above the said windows and apertures are projected to the elongated aperture 93 provided in the chamber 92 (see Figs. 8 and 9). The data to be listed and the code representations to be recorded which are set up by the indicator bars 55 and 56 are suitably illuminated by the elongated light sources designated 95 so that the images of the said representations are projected to the respective recording apertures 89 and 93 and the corresponding record mediums namely 90 and 94. In order to differentiate between the types of record mediums, it should be stated here that it is preferred that the record medium 90 comprises a photographic sheet or sensitized paper which is not transparent so that the record or work sheet formed by listing the individual items thereon is suitable, upon development, for such known applications for which the standard typewritten copies or the like are employed; whereas it is preferred that the record medium 94 comprises a transparent photographic film record suitable and adaptable, when developed for machine controlling purposes such as described, for example, in the above mentioned application.

The photographic paper 90 is shown disposed on a suitable supply reel 97 and is adapted to be fed through the supply rollers 98 and feed slot 99 to expose the sensitized areas thereof at the recording aperture 89 of the chamber 88. Disposed between the supply reel 97 and the take-up reel 100 and below the feed slot 99 are the paper feeding rollers 101 and 102. The roller 101 is secured to shaft 103 which also has attached thereto the ratchet wheel 104 adapted to be operated intermittently by the pawl mechanism 105 supported by the arm 106 to which lever 107 is pivotally attached. The said lever is adapted to be positioned periodically (to be explained later) to operate the said pawl and ratchet device to advance the said paper sheet thereby presenting progressively the sensitized areas of the paper to the recording position.

A suitable flexible driving connection is provided for the take-up reel in the form of the belt 108, pulley 109 fixed on shaft 110 and pulley 111 secured to shaft 103. Control contacts C-2 are also provided and as long as the said sensitized paper is fed to the recording position or adapted to be closed by means of the pivoted control lever 112 which is provided with an extension 113 adapted to engage the paper 90 by extending through a slot provided in the member 114 forming part of the throat through which the paper is fed.

The transparent film record 94 is disposed on the supply reel 115 and fed to the recording position at aperture 93 intermittently by the feed sprockets 116 and 117 fixed on shafts 118 and 119 respectively, and is then rewound on the take-up reel 120. Associated with the said shafts

is the gearing generally designated 121 which in turn is driven by gear 122 provided with a cam plate 123 which is part of a Geneva drive device, the other part being a cam disk as indicated at 125 which is secured to shaft 124 (Figs. 10 and 11). Also secured to the shaft 124 is the gear segment 126—a adapted to cooperate with gear 122 when the Geneva device comprising cam plate 123 and cam disk 125 are unlocked. Thus it should be understood that as shaft 124 rotates, the rotating cam disk 125 is adapted periodically and intermittently to control the rotation of gear 122 and the associated gearing 121 to advance the feed sprockets 116 and 117 thereby advancing the film record 94 sufficiently to present a completely new area of the film to the recording position at the aperture 93. The rotation of shaft 124 is controlled by magnet 126 and upon energization thereof causes the armature 127 to be withdrawn from the path of the pawl 128 pivotally mounted on member 129 which in turn is fixed to shaft 124 thereby engaging the clutch element 130 secured to shaft 131 which is positioned in axial alignment with shaft 124. Shaft 131 (Fig. 8) is adapted to be rotated by means of the gear 132 secured thereto and cooperating with the gear train generally designated 85.

By virtue of the described gearing arrangement the feeding of the said record mediums is effected synchronously with respect to the positioning of the indicator bars 55 and 56 and the feeding of the control film record 20, since the driving means for all the said elements are directly connected to the main driving gear 45 (Fig. 4). The intermittent advancing of the record mediums is effected after the scanning cycle, that is, immediately after the group of control spot representations on the film control record 20 have been presented to the analyzing station. Shortly before the advancement of the said record mediums is effected and immediately after the scanning of the film control record, the shutter mechanism, which may be of any well known type, associated with the lens system indicated at 81 and 91 are adapted to be operated by means of the control rods 133 and 134 respectively.

Provision is made to advance the record sheet 90 and trip the shutter mechanism of the lens system 81 by means of the cams 135 and 136 (Figs. 8 and 10) secured to shaft 131. After the indicator bars 55 and 56 have been raised to their respective positions, or in other words, upon completion of the sensing cycle the control rod 55 133 which is adapted to ride on the cam 135 is adapted to drop off the high point of the said cam to trip the shutter mechanism thereby permitting the data set up on the bars 55 to be recorded photographically on the record sheet 90.

Immediately after exposure of the said record sheet it is adapted to be spaced to the next position by means of the cam 136. The high spot of said cam is effective to position the pivoted arm 137 to the left as viewed in Fig. 7 thereby urging the lever 107 and pawl 105 forwardly to advance the ratchet 104, feed roller 111 and the record sheet 90, thus presenting an unrecorded portion of the sensitized paper to the aperture 89 for exposure.

Shaft 124 is also provided with a cam element 138 to trip the shutter mechanism of the lens system 91 by permitting the control rod 134 to drop off the high point of the cam at the same 75

time the shutter mechanism of lens system 87 is tripped by rod 133.

It should be mentioned at this time that control contacts C-3 are provided to be closed by the film record 94 as long as the film record is advanced to the recording position due to the pivoted control lever 139, however, when the film supply is exhausted the said lever is adapted to rotate in a counterclockwise direction thus permitting the C-3 contacts to be opened, the purpose of which will be explained in connection with the circuit diagram and operation of the machine which will now be described.

Operation of the machine

Referring now to Fig. 12a and Fig. 12b the operations of the machine will be described in connection with the circuit diagram therein. Upon closure of the switches 150 the motor 47 and light sources 32 and 95 are energized. Operation of the motor effects rotation of gears 45 and 44 and clutch element 43, also gear 17, shaft 78 (Fig. 4), and clutch element 79 (Fig. 7). Now upon depression of the start key closing contacts 151, a circuit is completed from conductor 152 to normally closed contacts 153 of the stop key, contacts 151 and coil of relay R-1 to conductor 154, energizing relay R-1. A holding circuit for the said relay is established by the contacts R-1a which are now closed and is as follows: conductor 152, contacts 153, contacts C-1, C-2, C-3, and R-1a, coil of relay R-1, conductor 154. The said relay now remains energized until the stop key is operated or any one of the record medium control contacts C-1 to C-3 are opened due to the record medium supply being exhausted. Connected in parallel to the coil of relay R-1 is the control magnet 37 which is energized at the same time as the said relay and maintained energized by the described holding circuit.

Energization of magnet 37 (Fig. 4) releases the pawl 42 to permit engagement thereof with the rotating clutch element 43 to drive shaft 28 and feed sprocket 30 and gears 49, 50 and 51 and shaft 27 and feed sprocket 29 thereby advancing the transparent film record 20 to the sensing station designated 31. The differentially positioned data representations 22 (Fig. 1) which in effect are light modifying spots or areas are then, upon presentation to the sensing aperture 31, effective to intercept the light rays emanating from the light source 32. Assume that all the different record mediums, namely, film 20 shown in Fig. 4, and film 94 and the photographic paper 90 shown in Fig. 5, are all properly positioned and aligned in the said associated advancing means before the switches 150 are operated. Upon operation of the said switches the said light sources are energized. At this time no control spots are presented to the sensing or analyzing station shown in Fig. 4. Therefore the light rays are impinged upon the quartz rods 35 and the associated photo-cells 34 rendering the said cells operative. The individual amplifiers associated with the photo-cells are arranged so that the amplifying systems are conditioned at such times so that substantially no current flows in the output circuits thereof and the relays A-1 to A-9 connected therein. It is seen now that this condition exists at all times at the analyzing station except whenever the control spots on the film 20 are presented thereto to intercept the light rays impinging on the photo-cells. At such times, that is, when the

light rays are intercepted, the individual amplifiers are rendered operative, in the sense that current is permitted to flow in the output circuits thereof to energize the corresponding relay coils connected therein. The circuit arrangements between the photo-cells and electronic amplifier devices are well known in the art so that further description is not deemed necessary.

It is understood now that whenever the control spots or data representations shown on the film 20 in Fig. 1 are presented to the analyzing station of the machine, detection or sensing thereof is effected by means of the light rays intercepted thereby and thus conditioning the corresponding amplifying systems to become conductive thereby energizing the associated relays of the group A-1 to A-9 connected in the output circuits thereof. Continuous feeding of the film control record is effected as long as magnet 37 remains energized. Upon energization of any of the relays A-1 to A-9 operation of the associated contacts A-1a to A-9a is effected to establish circuits from conductor 152 to contacts C-4 (closed at each control spot position by means of the associated cam 52-a), contacts A-1a to A-9a, conductors 156 to the corresponding control magnets 73 and 73-a and conductor 154 to energize the said magnets.

Now assume that both the switches 157 and 158 are closed and it is seen that the magnets 82 and 126 are energized as long as relay R-1 remains energized by means of the associated operated contacts R-1b. Energization of the said magnets renders operative the control elements of the photographic recording section; magnet 82 causes pawl 84 to be released to engage the rotating clutch element 79 thereby operating the indicator bars 55 and 56 in synchronism with the advancement of the film control record 20 to the analyzing station, and in addition thereto by means of the gearing 85 shaft 131 is rotated to effect operation of the lens system 87 and the feeding means for the photographic paper 90, the operation thereof being in timed relation with the presentation of the control spots to the sensing means and the displacement of the indicator bars 55 and 56. Energization of magnet 126 releases pawl 128 to engage the rotating clutch element 130 disposed on shaft 131 to drive shaft 124, the rotation of which is adapted to operate the lens system 91 and advancing means of the film 94, of the film recording or reproducing section of the machine. It was mentioned hereinbefore that the operation of the said lens system and advancing means for the film and photographic paper occurred simultaneously provided both the switches 157 and 158 are closed. It is obvious that by opening switch 158 the film reproducing mechanism is rendered inoperative. If it is desired to render inoperative the said film reproducing mechanism, then the switch 159 should be closed to shunt the contacts C-3 controlled by the film record 94.

It should now be understood that upon energization of the control magnets 73 and/or magnets 73-a by means of the differentially timed impulses initiated by the contacts A-1a to A-9a and contacts C-4, the corresponding stop pawls 70 are released to interrupt the movements of the indicator bars 55 and 56 at such positions so that the bars 55 present the numerical data corresponding to the sensed data representations on film record 20 to the windows 75 so that the recording thereof is effected upon the photographic paper 90. In this manner the data sensed on 75

film record 20 is adapted to be listed photographically on the sensitized paper medium 90 as shown in Fig. 2. The bars 56 are positioned so that the indicator spots 58 are differentially positioned within the elongated openings 76 so as to represent by their positions the data sensed on the film record 20. Upon exposure of the differentially positioned spots 58, and the data set up in the windows 75 to the transparent photographic film 94, a machine control film record is adapted to be produced bearing differentially positioned control spots or representations which are in effect the light modifying areas for controlling the conditioning of light responsive means and operations of a machine similarly as described hereinabove. In fact, in accordance with the example chosen, the machine control film record produced by exposure of the film 94 is identical to the film control record 20 shown in Fig. 1.

While there has been shown and described and pointed out the fundamental novel features of the invention as applied to a single modification, it will be understood that various omissions and 25 substitutions and changes in the form and details of the device illustrated and in its operation may be made by those skilled in the art without departing from the spirit of the invention. It is the intention therefore to be limited only as 30 indicated by the scope of the following claims.

What is claimed is as follows:

1. A record controlled recording machine for recording character images upon a light sensitive film in accordance with the data representations formed and sensed on the control records comprising an objective and intermittent film moving means, shutter means to control the exposure of the light sensitive film through the objective to the characters, means for feeding a film control record bearing a plurality of data control spots variably positioned longitudinally on the said control record, the different positions of the control spots denoting the values of the data representations, means for sensing the data control spots comprising a source of light rays and light responsive means controlled by the light rays modified by the said control spots, means controlled by the light responsive means including means for converting the sensed data control spots into characters represented by the said control spots, and means connected with the last mentioned controlled means for controlling the said shutter and film moving means to effect exposure of the light sensitive film to the character images, while the film is stationary in a predetermined time relationship with the sensing of the said control spots.

2. A record controlled recording machine for recording indicated data images upon a light sensitive film in accordance with the data representations formed on the control records comprising an objective and intermittent film moving means, means to control the exposure of the light sensitive film through the objective to the indicated data, means for feeding a film control record bearing a plurality of control data spots variably positioned longitudinally on the said control record, the different positions of the control spots denoting the values of the data representations, means for sensing the data control spots comprising a source of light rays and light responsive means controlled by the light rays modified by the said control spots, means for indicating selectively and graphically the data represented by the sensed control spots having means

controlled solely and directly by the light responsive means for controlling the selective operations of the indicating means, and means connected with the said indicating means for controlling the said film moving and exposure control means to effect exposure of the light sensitive film to the said indicated data images, while the film is stationary, in a predetermined time relationship with the sensing of the said control spots. 5

3. A record controlled recording machine for recording indicated data images upon a light sensitive film in accordance with the data representations formed on the control records comprising an objective and intermittent film moving means, means to control the exposure of the light sensitive film through the objective to the indicated data, means for feeding a film control record bearing a plurality of data control spots variably positioned longitudinally on the said control record, the different positions of the control spots denoting the values of the data representations, means for sensing the data control spots at different times comprising a source of light rays and light responsive means controlled at different times by the light rays modified by the said control spots, means controlled by the light responsive means for initiating differentially timed impulses at such times when the control spots are effective to modify the light rays, means controlled by the initiated timed impulses including means for indicating selectively and graphically the data represented by the sensed control spots, and means connected with the indicating means for controlling the said film moving means and exposure control means to effect exposure of the light sensitive film to the said indicated data images, while the film is stationary, in a predetermined time relationship with the sensing of the said control spots. 20

4. A record controlled recording machine for recording indicated data images upon a light sensitive film in accordance with the data representations formed on the control records comprising an objective and intermittent film moving means, means to control the exposure of the light sensitive film through the objective to the indicated data, means for feeding a film control record bearing a plurality of data control spots variably positioned longitudinally on the said control record, the different positions of the control spots denoting the values of the data representations, means for sensing the data control spots comprising a source of light rays and light responsive means controlled by the light rays modified by the said control spots, electron discharge means controlled by the light responsive means for initiating control impulses, data indicating means and control circuits therefor, said control circuits energized by the control impulses for controlling the indicating means to indicate the data represented by the sensed control spots, and means connected with the said indicating means for controlling the said film moving and exposure control means to effect exposure of the light sensitive film to the said indicated data images, while the film is stationary, in a predetermined time relationship with the sensing of the said control spots. 50

5. A record controlled recording machine for recording selected indicia images upon a light sensitive film in accordance with the data representations formed on the control records comprising an objective and intermittent film moving means, means to control the exposure of the light sensitive film through the objective to the se- 75

- lected indicia, means for feeding a film control record bearing a plurality of data control spots variably positioned longitudinally on the said record, the different positions of the control spots 5 denoting the values of the data representations, means for sensing the data control spots comprising a source of light rays and light responsive means controlled by the light rays modified by the said control spots, means controlled 10 by the light responsive means including means for indicating selectively the data represented by the sensed control spots, means for indicating selectively differently positioned control marks corresponding to the sensed control spots, and means connected with the said indicating 15 means for controlling the said film moving and exposure control means to effect exposure of the light sensitive film to the selected indicia images comprising the said indicated data and control 20 mark images, while the film is stationary, in a predetermined time relationship with the sensing of the said control spots.
6. A record controlled recording machine for recording indicia images upon a light sensitive medium in accordance with the data representations formed on the control records comprising an objective, means to control the exposure of the light sensitive medium through the objective 25 to the indicia, means for feeding a film control record bearing a plurality of data control spots variably positioned longitudinally on the said control record in different columns, the different positions of the control spots in the said columns 30 denoting the values of the data representations, means for sensing the data control spots comprising a source of light rays and light responsive means controlled by the light rays modified by the said control spots, a plurality of indicia indicating elements, means controlled by the light 35 responsive means for conditioning selectively the said elements for indicating the different positioning of the control spots in various columns to correspond to the sensed control spots, and means connected with the indicating elements 40 for controlling the first mentioned means to effect exposure of the light sensitive medium to the indicia images in a predetermined time relationship with the sensing of the said control 45 spots.
7. A record controlled recording machine for recording indicated data images upon a light sensitive medium in accordance with the data representations formed on the control records comprising an objective, means to control the exposure of the light sensitive medium through the objective to the indicated data, a sensing station, means for feeding a control record having differentially positioned data representations thereon 50 past the sensing station, means at the sensing station for sensing at differential times the data
- representations including means for initiating control impulses at the different times the data representations are sensed, a plurality of data indicating elements, means for positioning the said elements in timed relationship with the 5 sensing of the data representations, control means responsive to the said control impulses for maintaining the positioned indicating elements in a fixed position for indicating the data at a predetermined point corresponding to the sensed data representations, and means connected with the positioning means for controlling the first mentioned means including means for effecting exposure of the light sensitive medium to the 10 said indicated data images upon completion of the sensing of the said data representations.
8. A record controlled recording machine for recording indicated data images upon a light sensitive medium in accordance with the data 20 representations formed on the control records comprising an objective, means to control the exposure of the light sensitive medium through the objective to the indicated data, a sensing station, means for presenting successively there- 25 to groups of coded data representations, means for sensing each group of data representations during a predetermined timed interval, a plurality of data indicating elements and control means therefor controlled by the sensing means for selectively conditioning the indicating elements, during the said timed interval, to indicate the data at a predetermined point corresponding to the data representations sensed, and means connected with the data indicating elements for controlling the first mentioned means including means rendered operative at the end of the said predetermined timed interval upon completion 30 of the sensing operation to effect exposure of the light sensitive medium to the said indicated data images.
9. A photographic recording device for recording indicated data images upon a light sensitive medium comprising an objective, means to control the exposure of the light sensitive medium through the objective to the indicated data, a plurality of data indicating elements, individual control means for conditioning each data indicating element to represent predetermined data 35 including individual control circuits therefor, means to energize selectively the said control circuits to represent predetermined data thereby controlling the said control means and conditioning of the data indicating elements to represent 40 the predetermined data, and means connected with the said control means for controlling the first mentioned means to effect exposure of the light sensitive medium to the selected data images.

JAMES W. BRYCE.
